UNITED STATES PATENT OFFICE.

ALBERT E. FISK, OF CHICAGO, ILLINOIS, ASSIGNOR TO FREYN, BRASSERT & COMPANY, OF CHICAGO, ILLINOIS, A CORPORATION OF MAINE.

SCREENING DEVICE.

Application filed February 7, 1919. Serial No. 275,540.

To all whom it may concern:

Be it known that I, ALBERT E. FISK, a citizen of the United States, residing at Chicago, in the county of Cook and State 5 of Illinois, have invented certain new and useful Improvements in Screening Devices, of which the following is a specification.

My invention relates to a device for screening coke, coal, gravel or other similar material, and has for its primary object the provision of a revolving screen which will not clog up and which will thoroughly remove fine particles from the material which is being screened, and which will not crush 15 material being screened.

Another object of my invention is the provision of a screening device which is self cleaning in its operation, and which will not require constant attention to keep it in 20 working condition.

Another object of my invention is the provision of a screening device which will remove all fine braise from coke without breaking up the coke and without the use of a 25 mechanical device for stirring the coke, which is sometimes used with a stationary screen, as otherwise as the mixed coke and coke braise moves over the screen, only the braise carried by the lower strata of coke 30 will be removed. My invention gives to the coke or other material being screened a tumbling action thus thoroughly removing all braise or dust which is carried by the material.

35 My improved screen is particularly adapted for use in screening coke in the operation of blast furnaces and is adapted to be installed underneath the bin so that the coke will be discharged through 40 an opening in the bottom of the bin down upon the screening device and which when started in operation screens and delivers the coke from the bin into a chute where it is discharged into a skip.

45 Another and further object of my invention is the provision of a screening device comprising in combination a revolving drum to which is secured a plurality of outwardly extending forks the tines of which are 50 adapted to pass between the tines of stationary forks which project inwardly towards the said drum and which act as receiving and discharge forks for the material to be screened. The tines comprising all of 55 these forks are adapted to be easily removed

and to be replaced as worn, as it is well known that material such as coke or the like is very abrasive in its action and wears down screens or metal over which it passes very rapidly. 60

Another and further object of my invention is a provision of a screen which is simple and efficient in operation and which can be easily installed, and which will be inexpensive in operation and requires no 65 attention to keep the screens from becoming clogged during the operation of the device.

These and other objects of my invention will be more readily understood by reference to the accompanying drawings and in 70 which—

Figure 1 is a vertical sectional view of my improved screen.

Figure 2 is a horizontal sectional view looking downward upon the revolving drum 75 and forks; and,

Figure 3 is a sectional view showing the manner of arrangement of the tines of the forks.

Referring now specifically to the drawings 80 a hopper 9 is shown composed of plates 10, 10 and within which a revolving drum 11 is mounted upon a shaft 12, the ends of the shaft being mounted within the side walls 10, 10. At the upper side of the hopper 9 is 85 a receiving spout 13 which leads from a bin or other suitable source of supply, and through which the material flows downward upon a receiving fork, hereinafter described, by action of gravity. A discharge spout 14 90

for the coarse or screened material is provided, and another discharge spout 15 for the fine material is also provided. At the lower end of the receiving spout 13 is a receiving fork 16 comprising a plurality of 95 spaced tines 17—17, which are held in position by being inserted between spaced members such as 26 and 26^a at their rear ends and held in position by a wedge 26^b driven under each tine. A pair of rods 18 and 19 100 affords means for holding the members 26^a, 26^b securely in position and the members 26, 26 are held by means of bolts 18^a 19^a. The tines are notched or recessed on their upper sides at their rear ends so as to engage the member 26 and prevent movement of the tines. The tines 17 which make up the receiving fork 16 project inwardly towards the drum and their inner ends are just out of contact with the revolving drum 11. The 110

drum 11 is composed of a plurality of annular members 20—20, spaced apart in the manner hereinafter described and has secured thereto a plurality of forks 21, 21. 5 The said forks 21 comprise a plurality of spaced tines 22, 22 which are secured to the drum 11 on their inner ends and project outwardly from the cylinder 11. The forks 21, 21 are made up of a plurality of spaced tines 10 22, 22, each of the tines being spaced apart a pre-determined distance, depending upon the fineness of the particles it is desired to remove from the material, and are secured on their inner ends to the drum 11 by any 15 suitable means, as for example a plurality of rods 23, 23 extending longitudinally of the drum 11 and passing through the members 20, 20, the rear ends of the tines being positioned between the members 20, 20, and 20 forming the means for spacing the said members apart. A discharge fork 24 is provided, the tines of which are secured to the lower wall of the discharge opening 14 by means of a pair of rods 25 and 25^a, and projects upwardly so that its inner end is just 25 out of contact with the drum 11. The discharge fork 24 is composed of a plurality of tines spaced apart a predetermined distance so that the tines of the revolving forks 30 21, 21 will pass between the tines of the discharge fork 24 as the drum rotates, and has its tines recessed on their under sides a short distance from its rear end and into which the rod 25 is inserted, the rear end of the 35 tines of the said fork 24 being recessed also and rest upon the rod 25^a thus allowing for the easy removal and renewal of the tines simply by lifting up the forward end of the tine and pulling it out of place. It will thus 40 be understood that the receiving fork 16 and the discharge fork 24 have their tines spaced apart, and offset out of the path of travel of the tines of the revolving forks which have their tines spaced apart the same 45 distance as the receiving and discharge forks, the space between the tines depending upon how much of the fine material it is desired to remove. The tines of the revolving forks 21, 21 thus pass between the tines of the receiving and discharge forks, thus picking 50 up the coarse material lying upon the receiving fork and allowing the fine material to drop downward between the tines of the receiving fork. The nuts on the bolts 23—23 55 are drawn up tightly so as to hold the tines 22—22 of the revolving forks between the spacing members 20—20 of the drum 11 and preventing the tines from pitching forward and dropping out or the coke from knocking them out as it falls forward onto the 60 back of the fork in front of the one upon which it has been carried from the receiving fork, as hereinafter described, and yet allowing for the removal of the tines in case it 65 is desired to renew or replace them. An

electric motor 29 is provided to which a belt 30 is secured leading to a pulley 31 mounted upon the shaft 12 and secured in any suitable manner to the drum 11, thus providing means for rotating the drum 11. 70

The method of operation of the device is as follows:

The chute 13 leads to a hopper or bin containing material to be screened and conveys the material down to and upon the receiving fork 16. It will be understood that as long as drum remains stationary material is prevented from coming through the inlet chute 13 and thus the bottom of the hopper is securely closed. The motor 29 may be started thus starting the drum 11 revolving, carrying with it the revolving forks 21, 21 which pass upward between the tines of the receiving fork 16 and carry the coarser material over until it reaches a point above the drum where it is dropped downward upon the revolving fork immediately preceding the fork which has carried the coarse material off the receiving fork, more of the finer material will pass downward between the tines of the revolving fork and the discharge fork and out through the chute 15 and the coarse material will be discharged off the back of the revolving forks 21 and through the chute 14. Should any pieces of material become lodged between the tines of the forks 21, it will be dislodged as the tines of the revolving forks pass between the tines of the discharge fork 24. The fine material will pass between the tines of the receiving fork 16, also between the tines of the revolving forks 21 as the material is thrown from the forward side of the revolving forks on to the back of the revolving fork immediately in front thereof, and on downward between the tines of the discharge fork 24. It will thus be understood that when the skip is full or it is desired to stop the flow of the material from the coke bin, the motor is stopped, thus stopping the revolving of the drum and preventing the material from passing downward through the inlet chute 13. It will also be understood, because of the manner of attaching the tines of the revolving forks and discharge fork to the respective bases which holds them in position, they may be readily removed should a tine become worn or broken in operation by lifting up the tine at its forward end, thus disengaging the tine from the bolts which holds it in position, when it can be slipped out and a new tine put in its place. The tines of the receiving fork can also be replaced readily by removing the wedge 26^b and allowing the tine to drop downward and out of engagement with the member 26^a when the tine can be pulled out and a new one inserted, and the wedge 26^b replaced. It will be further understood that the sizes of the inlet 130

openings and discharge openings may be varied as circumstances require for the particular operation in hand.

It will also be understood that coke carried by the revolving forks will be given a tumbling action so as to take out of the coke all of the braise and dust, and also that the forks may be set at such angles to increase the tumbling of the coke as it passes over the drum and through the apparatus. And furthermore that a number of these devices may be arranged so as to grade coke or coal or other material, one unit taking out one size and the residue passing on to another unit and so on through any number desired, all of which arrangement I consider within the spirit and scope of my invention.

While I have described more or less precisely the details of constructions which I employ, I do not wish to be understood as limiting myself thereto, as I contemplate changes in form and the proportion of parts and the substitution of equivalents as circumstances may suggest or render expedient without departing from the spirit or scope of my invention.

I claim:

1. A screening device comprising a casing having a receiving hopper and a plurality of discharge openings at the lower side of said hopper, a revolving drum, sets of peripherally extending tines secured to said drum, a set of spaced tines at the bottom of said receiving hopper forming a holding and receiving element for the material to be screened, and a set of spaced tines across one of said discharge openings forming a discharge element for the coarse material.

2. A screening device comprising a casing having a receiving hopper at its upper side and a plurality of discharge openings at the lower side thereof, a revolving drum, sets of peripherally extending tines secured to said drum, each set of said tines being arranged in the same plane, a set of holding tines secured to said casing and extending across the bottom of said receiving hopper, and a set of spaced tines across one of said discharge openings forming a discharge element for the coarse material.

3. A screening device comprising a casing having a receiving hopper at its upper side and a plurality of discharge openings at the lower side thereof, a revolving drum provided with sets of spaced peripherally extending tines, each set being arranged in

the same plane, a set of spaced tines extending across the bottom of said receiving hopper and forming a receiving and screening element for the material to be screened and a discharge element comprising a set of spaced tines across one of said discharge openings forming a discharge element for the coarse material.

4. A screening device comprising a casing having a receiving hopper at the upper side thereof, a plurality of discharge openings at the lower side thereof, a revolving drum, sets of peripherally extending tines secured to said drum, each set being arranged in the same plane, a set of spaced tines extending across the bottom of said receiving hopper and above one of said discharge openings, and a second set of spaced tines secured to said casing forming a discharge element for the coarse material, the said receiving element forming a screening and holding element across the bottom of said receiving hopper.

5. A screening device comprising the combination of a casing having a receiving hopper at its upper side, and a plurality of discharge openings at its lower side, a revolving drum, sets of spaced peripherally extending tines secured to said drum, each set being arranged in the same plane, a set of spaced tines detachably secured to said casing extending across the bottom of said receiving hopper and forming a screening and holding element for the material to be screened and a second set of tines secured to said casing forming a discharge element for the coarse screened material.

6. A screening device comprising a case having a receiving hopper at its upper side and a plurality of discharge openings at the lower side thereof, a revolving drum having sets of spaced peripherally extending tines detachably secured thereto, sets of spaced tines detachably secured to said casing and extending across the bottom of said receiving hopper forming a receiving and screening element for the material to be screened and a second set of tines detachably secured to said casing extending across one of said discharge openings forming a screening and discharge element for the material thrown thereon from the screening tines secured to said drum.

Signed at Chicago, Illinois, this 28th day of January, 1919.

ALBERT E. FISK.
